UNITED STATES PATENT OFFICE.

WILLIAM C. STEWART, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MACHINE FOR WORKING UPPERS OVER LASTS.

Application filed January 19, 1920. Serial No. 352,324.

To all whom it may concern:

Be it known that I, WILLIAM C. STEWART, a subject of the King of England, residing at Swampscott, in the county of Essex and 5 State of Massachusetts, have invented certain Improvements in Machines for Working Uppers Over Lasts, of which the following description, in connection with the accompanying drawings, is a specification, like 10 reference characters on the drawings indicating like parts in the several figures.

This invention relates to machines for working uppers over lasts and is herein shown as incorporated in a machine having 15 means for pulling the upper over the last and means for wiping the upper into lasted position round the toe, although it is to be understood that in many of its aspects the invention is not limited to machines including both pulling-over means and lasting 20 means nor to machines in which the means for laying the margin of the upper inwardly over the sole comprises end lasting wipers.

In the operation of overlaying means, 25 such as wipers, it is important not only that the upper be conformed closely to the margin or feather of the sole or insole (hereinafter termed generically the "sole"), but that it be held also against substantial loss 30 of such tension as may have been applied in conforming it to the top and the lateral periphery of the last. It is also desirable that in the overlaying operation the upper be still further tightened over the lateral periphery of the last to produce a smooth and 35 uniform contour along the edge of the sole. An important feature of this invention consists in novel means whereby satisfactory results in these different respects are insured.

40 The construction shown comprises an upper-engaging presser device which projects over the feather of the sole in position to bend or press the margin of the upper progressively outward over the wipers as the latter move inwardly and thus to increase the effectiveness 45 of the wipers in holding the upper against loss of tension and in tightening it over the last. Advantageously, in the construction shown, the presser device has a beveled outer edge portion projecting over 50 and spaced from the feather of the sole to provide a restricted opening into which the upper is to be wedged by the wipers. In

the illustrative construction the overwiping means and the presser device are combined 55 with means for pulling the upper over the last prior to the overwiping operation, and a further important feature of the invention resides in an organization of this character whereby insurance is afforded of the 60 effectiveness of the overwiping means in securing such control of the upper as to prevent objectionable loss of the pulling-over tension. In the construction shown, moreover, the presser device serves additionally 65 as a hold-down in engagement with the sole of the shoe on the bottom of the last, and still another advantageous feature is to be recognized in this aspect of the invention.

A further feature of the invention consists in novel means of control for a presser device or a hold-down, the presser and hold-down device in the construction shown being movably mounted on a pulling-over 70 gripper and connected to the sole rest of the machine by means of a latch which is operated automatically at a predetermined time 75 in the cycle of the machine to release the device and permit its withdrawal from operative position.

The invention also provides, as a further feature, novel means for imparting outdrawing movement to a gripper, this being accomplished in the construction shown by relatively movable members one of which is 85 carried by the gripper while another is part of the presser and hold-down device hereinbefore described, the different members 90 co-operating to wedge the gripper outwardly from the edge of the shoe bottom in its upper pulling movement.

Still another feature of the invention, designed particularly to insure against objectionable loss of tension in upper pulling machines, comprises novel gripper controlling 95 means whereby a gripper is caused to relax its hold on the upper only enough to permit relative slip between the gripper and the upper without substantial loss of tension as the overlaying means moves inwardly 100 to do its work. This result is accomplished in the construction shown by the co-operative action of two members one of which moves with the gripper and the other in a direction transverse to the direction of the 105 pull. Still another feature consists in the

combination of means for thus effecting a gradual release of the upper and a presser device co-operating with the overlaying means as hereinbefore set forth.

5 The above and other features of the invention, including certain details of construction and combinations of parts, will now be described with reference to the accompanying drawings and pointed out in the 10 claims.

In the drawings:

Fig. 1 is a view partly in side elevation and partly in vertical section of the head portion of a pulling-over and toe lasting 15 machine in which the invention is embodied,

Fig. 2 is a view in side elevation of the various instrumentalities that co-operate in pulling and lasting the toe, parts of the structure being broken away to show the 20 interior construction;

Fig. 3 is a perspective view of the toe gripper and associated parts of the structure, and

Figs. 4, 5 and 6 are views on an enlarged 25 scale illustrating successive stages in the operation of the machine.

The invention is herein shown as incorporated in a well-known type of pulling-over machine characteristic features of 30 which are shown and described in detail in United States Letters Patent No. 1,029,387 granted on June 11, 1912 upon an application of R. F. McFeely, and other features of which, relating more particularly to the 35 overwiping and fastening means are shown and described in Patent No. 1,280,613 granted on October 1, 1918 upon an application of Orrell Ashton, and for a more complete 40 understanding of such details of construction as are not hereinafter fully described reference may be made to these prior patents. Machines of this type include in their 45 general organization grippers for engaging and pulling the upper of a shoe at the toe end and at opposite sides of the forepart of a last positioned by means of a sole rest 2 and a heel rest 4, means for laying the margin of the tensioned upper inwardly over the sole on the bottom of the last, and 50 means for fastening the upper to the sole. Only one of the two opposite side grippers is shown in the drawings, this gripper comprising jaws 6 connected by a bar 8 to an updraw lever 10 which is pivoted on a bar 12 and is connected at its rear end through 55 a spring 14 to a vertically movable slide 16 operated by means of a cam 18 on a cam shaft 20 to which movement is imparted intermittently from a pulley 21 under the 60 control of well-known clutch mechanism characteristic of this type of machine. It will be understood that the upper at the opposite side of the last is pulled by similar mechanism also connected to the slide 16.

65 The toe gripper in the construction shown

comprises two pairs of relatively movable jaws 22 which are mounted in a casing 24 to turn about axes substantially perpendicular to the sole in conformity to the contour of the shoe round the toe, the outer or front 70 jaw of each pair being pivoted at 26 to the other jaw and connected to an operating member 28 which is slidable up and down in the casing. The two members 28 are connected to the lower end of the gripper bar 30 75 which extends downwardly within the casing 24 and is connected at its upper end to an updraw lever 32. The casing 24 is provided with lugs 34 which are arranged to engage a bracket 36 on the frame of the 80 machine to limit downward movement of the casing and to permit the bar 30 in its continued downward movement to impart opening movement to the pivoted gripper jaws, the gripper opening movement of the 85 bar being effected against the pressure of a spring 38 which bears oppositely against the casing 24 and the bar 30. In the initial portion of the upward movement of the bar 30 the spring 38 acts to hold the casing in 90 its lowermost position and thus to render the bar operative, by movement of the members 28, to close the jaws on the upper, and after the jaws have firmly gripped the upper 95 casing and both pairs of jaws are moved upwardly together by the action of the gripper bar to pull the upper.

The upper pulling movement is imparted to the toe gripper lever 32 through a spring 40 by the action of a vertically movable 100 slide 41 operated by a cam 42 on the cam shaft 20. If it is desired to open the toe gripper after the upper has been pulled in order, for example, to re-adjust the upper in the gripper jaws, this may be done by 105 the use of a pivoted lever 43 on the front end of the lever 32, the lever 43 being connected by gear teeth to a pivoted releasing member 44 which carries a lug 46 engaging under an offset portion of a slide 48 which 110 is mounted on the gripper bar 30 and is connected at its lower end to the casing 24. By pressing the lever 43 upwardly the slide 48 is elevated and upward movement is thus 115 imparted to the casing and to the two pairs of jaws while the bar 30 and the members 28 are held against such movement by the lever 32, and the pivoted jaws are thus 120 opened by the action of the members 28 a distance proportional to the extent of movement of the member 44. These features of construction of the toe gripper and of the 125 means whereby its jaws may be opened manually are substantially the same as in the disclosure of United States Letters Patent No. 1,137,566 granted on April 27, 1915 upon an application of Orrell Ashton, to which reference may be made for a more complete 130 understanding of the details of the structure.

It will be understood that in the opera-

tion of the machines of this general type the machine comes automatically to rest after the upper has been pulled by the grippers and while it is held under tension to permit the operator to observe the condition of the work and to make such adjustments as may be required. When the machine is again started, side clamping and supporting devices 50 are swung inwardly 10 into operative relation to the shoe, and either immediately, or following another pause in the cycle, the overlaying and fastening operations are performed. In common with the machine shown in prior Patent No. 1,280,613, the present machine includes devices for overlaying and fastening the margin of the upper at the opposite sides of the shoe and devices for wiping the upper into lasted position and for fastening it round 20 the toe end of the shoe. For an understanding of the present invention it is only necessary to refer in detail to the means for overwiping and fastening the upper at the toe. This means comprises an arm 52 which 25 is mounted to swing lengthwise of the shoe and carries at its lower end relatively movable wiper plates 54 which are advanced lengthwise of the shoe by the rearward movement of the arm and are simultaneously closed inward laterally of the shoe at 30 the opposite sides by the side overlaying and fastening devices in substantially the same manner as explained in said Ashton patent. As also described in said patent, the arm 52 carries a plurality of tack holders 56 and corresponding tack drivers 58 which are operated by a driver bar 60 for driving the several tacks in different locations round the toe to hold the upper in lasted position. 40 Rearward movement is imparted to the arm 52 by means of a slide 62 which is connected at its front end to the arm and is also operative to release the driver bar 60 when the tackers have been carried into proper 45 relation to the shoe. It will be understood that by the action of the same slide 62 the side overlaying and tacking devices are moved inwardly and rendered operative to drive their tacks. As in the machines described in said prior patents, the present machine is designed to effect an overdrawing movement of the side grippers 6 in advance of the inwardly coming side overlaying and tacking devices, such movement being controlled as usual by the action of a slide 64 which is moved rearwardly with the slide 62. It will be noted by reference to Fig. 1 that the slide 64 carries a roll in engagement with the rear face of the toe gripper bar 30 to position the toe gripper initially lengthwise of the shoe. In the present machine, however, no overdrawing movement of the toe gripper while holding the upper is contemplated, the gripper being held from rearward movement at the time when 65 the slide 64 moves rearwardly by means to be hereinafter described. In distinction also from the disclosure of prior Patent No. 1,280,613 it is contemplated that in the present machine the toe gripper will retain 70 its hold of the upper until after the machine has been started to effect the overlaying and fastening operations and that the wipers 54, instead of being positioned manually in engagement with the upper, will be entirely 75 automatic in their operation on the shoe, as will be more fully explained hereinafter. 80 For a purpose of the present invention the machine is provided with an upper engaging presser device which in the construction shown also serves as a hold-down in engagement with the sole in front of the sole rest 2, this device comprising a pair of presser members or plates 66 curved in approximate conformity to the curvature of 85 the edge of the sole round the toe and pivotally mounted on a pin 68 to permit them to swing inward laterally of the shoe, the pin being held detachably by means of a spring 90 pin 70 in a forwardly extending portion of a holder 72 which is pivoted at 74 on a slide 76 mounted in a guideway for upward and downward movement along the gripper casting 24. By reference to Fig. 2 and also to Figs. 4, 5, and 6, it will be seen that the plates 66 have a beveled outer edge portion 95 to provide a wedge surface which in the operative position of the plates projects outwardly over and faces the feather *a* of the sole and that a narrow space or opening is thus provided between the projecting edge of the plates and the feather of the sole into which the margin of the upper must be forced by the action of the wipers 54. As 100 the wipers close inwardly the plates 66 act to press or bend the margin of the upper outwardly over the wipers and thus to increase the effectiveness of the wipers in their frictional hold upon the stock and to render them effective to hold the upper against slip 105 earlier in their inward movement than if such a device were not provided. It will also be evident that the beveled edge portions of the plates act to wedge the upper downward against the feather of the sole, 110 the wipers in the construction shown being downwardly yieldable against the tension of a spring 78 as in the construction described in Patent No. 1,280,613. In order 115 to accommodate the plates 66 to different shapes or sizes of shoes, they are permitted to yield inwardly about their pivot 68 against the tension of a spring 80 which tends to spread them apart. They may thus project initially farther outward over the feather of the sole at the sides than is indicated in Fig. 2 and as the wipers close inwardly they may yield laterally of the shoe 120 125

in response to the pressure of the upper while acting with their outwardly bending and clamping effect on the upper at the sides as well as at the extreme end of the toe. For wide variations in shape and size different sets of plates may be used, the spring pin 70 readily yielding to permit such replacement.

The initial position of the presser plates 66 and their supporting means is indicated in Fig. 3, in which the slide 76 is held by means of a spring 82, which extends downwardly in a recess in the slide, in its uppermost position determined by engagement of a lug 84 at the lower end of the slide with the lower face of the casing 24. In this position of the parts the holder 72 is swung inwardly into substantially parallel relation to the slide 76 by a leaf spring 86 which at its lower end is fast on the holder 72 and at its upper end bears on a pin 88 on the slide. The presser plates 66 are thus positioned close to the gripper jaws for engagement with the sole when the shoe is presented to the machine and the margin of the upper is inserted within the jaws. In this position of the parts the holder 72 is locked against upward movement by means of a latch 90 which hooks under a projection 92 in a recess in the end of the sole rest 2, the latch being mounted on a pivot 94 on the holder 72 with its lower end normally pressed outward by a spring 96. The plates are thus held by the sole rest against upward movement away from the sole, and are also held by engagement of the end of the sole rest with the holder 72 against bodily rearward movement over the sole while the gripper is operated by the lever 32 to pull the upper.

In order to impart to the gripper a forward or outward movement relatively to the edge of the shoe bottom to cause the gripper jaws to clear the presser plates and the edge of the sole as well as to draw the upper forwardly at the toe, the holder 72 is provided with wedge faces 98 which co-operate with wedge faces 100 formed on lugs 102 on the casing 24 to wedge the gripper forwardly as it moves upwardly, the holder 72 being restrained from rearward movement by the action of the sole rest to cause it to serve as an abutment against the rearward pressure of the gripper. After the overwiping operation has been substantially or approximately completed the latch 90 is operated to release the holder 72 from the sole rest and permit the springs 82 and 86 to act respectively to move the slide 76 to its uppermost position relatively to the gripper and to swing the holder 72 inwardly toward the gripper. For this purpose there is utilized a further upward movement of the gripper during which its jaws are per-

mitted to slip over the margin of the upper as will be hereinafter explained. As the gripper is thus moved upwardly, lugs 104 upon the casing 24 are carried into engagement with inwardly projecting fingers 106 on the upper end of the pivoted latch 90 and act to swing the lower end of the latch forwardly until it disengages the projection 92 on the sole rest. The presser plates are thus withdrawn above the work out of the path of movement of the inwardly moving tacker mechanism and are returned to their initial position relatively to the gripper jaws.

In order to insure that the wipers 54 in co-operation with the presser plates 66 shall secure an effective hold of the upper such as to prevent loss of the pulling-over tension, the machine is provided with means for effecting a gradual release of the upper by the toe gripper as the wipers move inwardly, without permitting the gripper to lose substantial control of the upper until the wipers are sufficiently far advanced to render them effective to hold the upper. For this purpose power means is provided to operate the mechanism hereinbefore referred to as means whereby the toe gripper may be opened manually. As already explained, movement of the releasing member 44 by the action of the lever 43 draws the bar 48 and the gripper casing 24 upwardly along the relatively stationary gripper bar 30 and thus causes the pivoted front jaws of the gripper to open a distance proportional to the movement of the member 44. In the construction shown this member is provided with a depending portion upon which there is mounted a contact block 108 in position to be engaged by a roll 110 which is supported on the outer end of the slide 62. As the slide 62 is moved rearwardly to swing the arm 52 and its supported wiper and tacker mechanisms toward the shoe the roll 110 is carried into engagement with the block 108 and by the continued movement of the slide the member 44 is thus turned about its pivot in a direction to open the gripper jaws. Preferably the parts are so arranged that the roll 110 begins to operate the member 44 when the wipers have been moved substantially or approximately to the position illustrated in Fig. 4 and have thus begun to press the upper inwardly over the feather of the sole. The effect of the roll 110 on the member 44 is to cause the jaws to relax their pressure slightly on the upper, enough to permit them to slip over the upper under the influence of the updraw spring 40 which tends constantly to move the lever 32 and the gripper farther upwardly. In order that the gripper jaws may still engage the upper with sufficient pressure to render them effective to prevent substantial loss of the

tension of the upper until the wipers have advanced far enough to hold the upper effectively in co-operation with the plates 66, the front face of the block 108 which is engaged by the roll 110 is inclined to the direction of pulling movement of the gripper. It will be evident that by this construction the gripper releasing effect of the roll 110 in its rearward movement is partially counter-acted by the upward movement of the gripper and the block 108 as the jaws slip over the stock. Preferably the angle of inclination of the front face of the block 108 is so proportioned to the movement of the roll 110 that the roll after its initial action on the member 44 to cause the jaws to relax their pressure on the upper maintains the member in a substantially uniform relation to the gripper and thus keeps the pressure of the jaws substantially constant on the margin of the upper until the latter finally slips from between the jaws. The time when the roll 110 begins to act on the member 44 may be varied by adjustment of the block 108 forwardly or rearwardly on the depending portion of the member 44, the block being held in adjusted position by means of a clamping screw 111 and backed up by a set screw 112.

In the operation of the machine, as far as concerns the present invention, it may be stated briefly that a shoe is presented to the machine while the parts are in their initial positions indicated in Fig. 1. In thus presenting the work the margin of the upper is arranged within the open gripper jaws and the end face of the last is engaged with the inner jaws 22 which determine as usual the lengthwise position of the shoe in the machine. The initial relation of the plates 66 to the jaws 22 is such that when the shoe is thus positioned the plates engage the sole with their outer beveled edges projecting over the feather of the sole. Upon the starting of the machine the upper is pulled by the grippers, the plates 66 being held by the latch 90 in their initial relation to the sole and the toe gripper being wedged forwardly during its upward movement by the action of the co-operating wedge faces 98 and 100. The machine then comes to rest with the parts at the toe of the shoe positioned as indicated in Fig. 2. When the machine is again started, the side clamping devices 50 are moved into operative position and the overwiping and fastening operations are performed at the toe as well as at the opposite sides of the forepart. As the wipers 54 are moved rearwardly by the arm 52 and 60 are closed inward laterally of the shoe in the well-known manner described in the prior Ashton patent, they engage the margin of the upper and press it inwardly against and over the edge of the sole. It will be evident that as the wipers continue to move they become increasingly effective to clamp the upper against the sole while wiping it inwardly and that in the course of the inward movement of the wipers the plates 66 become effective to assist the wipers in their holding action on the upper by pressing against its inner surface and by bending it outwardly over the wipers and clamping it against them. At a time determined by adjustment of the block 108, but preferably when the wipers have advanced substantially or approximately to the position indicated in Fig. 4, the roll 110 becomes effective to turn the releasing member 44 slightly and thus to cause the jaws 22 to relax their hold on the upper sufficiently to permit it to slip as the wipers continue their inward movement. By the time the wipers have wedged the upper far enough into the space between the feather of the sole and the wedge faces of the plates 66 to render the wipers effective to hold the upper securely against loss of tension, the margin of the upper slips out from between the jaws 22. Substantially at this time the lugs 104 on the gripper casing become effective to swing the latch 90 far enough to release it from the sole rest member 92, whereupon the plates 66 are withdrawn from operative position. It will be evident that the time of such withdrawing movement of the plates 66, as well as the time when the gripper jaws begin to relax their pressure on the upper and permit it to slip, is determined by adjustment of the block 108, since the operation of the latch 90 is effected by the upward movement of the gripper in response to the lessened resistance. Upon release of the latch 90 and the upward movement of the slide 76, the sole rest is no longer effective to prevent rearward movement of the gripper and the usual overdraw springs 114 are permitted to act to swing the gripper rearwardly over the shoe as an additional safeguard against interference between the gripper and the wiper and tacker mechanism. Such rearward movement of the gripper is permitted by the slide 64 which, as hereinbefore explained, moves rearwardly in unison with the slide 62. As soon as the tackers have been advanced to the required position and have been operated to drive their upper fastening tacks as indicated in Fig. 6, the parts are returned to their starting positions and the shoe is released. In such return of the parts the toe gripper is moved forwardly to its initial position by the slide 64 and is moved downwardly by the lever 32 until the latch 90 again hooks under the member 92 on the sole rest.

While the invention is herein illustrated by reference to turn shoe work, it will be understood that the invention is not limited

in utility to the manufacture of this particular kind of shoe. It will also be understood that in many of its aspects the invention is not limited to overlaying means or upper fastening means of the particular type illustrated, and that, in general, variations in mechanical details are contemplated within the spirit and scope of the claims.

Having described the invention, what I claim as new and desire to secure by Letters Patent of the United States is:

- 5 1. In a machine of the class described, the combination with means for laying the margin of an upper inwardly over a sole on a last, of an upper engaging presser device arranged to be positioned on the sole and having an upper engaging face formed to project from the sole outwardly over the overlaying means on the opposite side of said 15 means from the margin of the sole to bend the margin of the upper outwardly over said means in the overlaying operation, an automatically controlled means for maintaining said presser device in operative position and 20 for withdrawing it to permit the fastening of the upper.
- 15 2. In a machine of the class described, the combination with a wiper for wiping the margin of an upper inwardly over the feather of a sole on a last, of an upper engaging presser device arranged to be positioned on the sole and having a beveled edge portion formed to project over the feather of the sole in position to bend the margin 30 of the upper progressively outward over the wiper as it is wiped inwardly, and controlling means automatically operative in time relation to the wiper to withdraw said presser device from operative position.
- 35 3. In a machine of the class described, the combination with a wiper for wiping the margin of an upper inwardly over the feather of a sole on a last, of a presser device arranged to be positioned over the feather of the sole in engagement with the sole inwardly of the feather, said device having an upper engaging face opposed to and spaced from the feather of the sole to provide a restricted upper receiving opening 40 between it and the sole, means for holding said device against bodily inward movement with the wiper as the upper is forced by the wiper into said opening, and spring means for withdrawing said device from the sole.
- 45 4. In a machine of the class described, the combination with a wiper for wiping the margin of an upper inwardly over the feather of a sole on a last, of a presser device arranged to be positioned on the sole and having an edge portion provided with an outwardly directed wedge surface, and automatic means for positioning the device initially with its wedge surface pro-

jecting over and facing the feather of the sole to wedge the upper against the feather of the sole as it is wiped inwardly and for holding said device in position to effect such wedging action on the upper.

5. In a machine of the class described, the combination with a wiper for wiping the margin of an upper inwardly over the feather of a sole on a last, of a hold-down for engaging the sole on the bottom of the last, said hold-down having a surface 75 formed to extend at an angle to the plane of the sole in position for engaging the margin of the upper and bending it outwardly over the wiper as it is wiped inwardly, and automatically controlled means for positioning 80 the hold-down against the inward pressure of the wiper and for thereafter releasing it for movement out of operative position.

6. In a machine of the class described, the combination with end embracing wipers and means for operating them to wipe the margin of an upper inwardly over a sole round the end of a last, of a presser device arranged to be positioned on the sole with a portion projecting over the margin of the sole and to engage the upper and bend it progressively outward over the wipers as they move inwardly for increasing the frictional hold of the wipers on the upper, means for holding said device against movement rearwardly over the sole in response to pressure of the wipers, and spring means arranged to be tripped to withdraw said device from the sole.

7. In a machine of the class described, the combination with end embracing wipers and means for operating them to wipe the margin of an upper inwardly over the feather of a sole round the end of a last, of a device arranged to be positioned on the sole 105 and having an edge portion to project over the feather of the sole round the end of the shoe and spaced from the feather of the sole to provide a restricted upper-receiving opening between it and the sole, and automatic means for holding said device over the feather of the sole against the pressure of the wipers as the upper is forced by the wipers into said opening and for thereafter withdrawing said device from operative 110 position.

8. In a machine of the class described, the combination with end embracing wipers and means for operating them to wipe the margin of an upper inwardly over the feather of a sole round the end of a last, of a hold-down arranged to engage the sole inwardly of its feather edge to hold the sole in position on the bottom of the last, said hold-down having an outer edge portion curved 120 in substantial conformity to the curve of the edge of the sole and provided with an outwardly directed wedge surface project-

ing over and facing the feather of the sole to wedge the upper against the feather of the sole as it is wiped inwardly and controlling means automatically operative to position said hold-down for engagement with the sole and to withdraw it from operative position.

9. In a machine of the class described, the combination with end-embracing wipers and means for operating them to wipe the margin of an upper inwardly over the feather of a sole round the end of a last, of a device arranged to be positioned on the sole and provided with an outwardly directed wedge surface projecting over and facing the feather of the sole for engagement with the upper, said device comprising a pair of plates yieldably movable laterally of the shoe in response to pressure of the upper in the overwiping operation.

10. In a machine of the class described, the combination with end embracing wipers and means for operating them to wipe the margin of an upper inwardly over the feather of a sole round the end of a last, of a presser device arranged to be positioned over the sole and having an outwardly directed edge portion for engagement with the margin of the upper round the end of the last in the overwiping operation, said device comprising a pair of plates mounted to swing inwardly laterally of the shoe in response to pressure of the upper, and means for holding said device from bodily movement lengthwise of the shoe in response to such pressure.

11. In a machine of the class described, the combination with means for laying an upper inwardly over the margin of a sole on a last, of a presser device arranged to be positioned over the sole and to engage the margin of the upper and bend it progressively outward over the overlaying means in the course of the overlaying operation, a device movable inwardly over the sole for fastening the upper in overlaid position, and means automatically operative to move said presser device out of its operative position prior to the operation of the fastening device.

12. In a machine of the class described, the combination with a wiper mounted for movement to wipe an upper inwardly over the feather of a sole on a last, of a presser device arranged to be positioned on the sole and to engage the margin of the upper on the opposite side from the wiper for increasing the frictional hold of the wiper on the upper as the wiper moves inwardly, a tacker movable inwardly with the wiper, and means for moving said presser device out of its operative position to permit the operation of the tacker.

13. In a machine of the class described, the combination with a wiper mounted for

movement to wipe an upper inwardly over a sole on a last, of a presser device arranged to be positioned on the sole with an edge portion projecting outwardly for engagement with the upper to bend it outwardly over the wiper in the overwiping operation, and means automatically operative in time relation to the wiper to withdraw said device from operative position prior to the completion of the operation of the machine on the shoe.

14. In a machine of the class described, the combination with a wiper mounted for movement to wipe an upper inwardly over the feather of a sole on a last, of a presser device arranged to be positioned over the sole and to engage the margin of the upper on the opposite side from the wiper for increasing the frictional hold of the wiper on the upper as the wiper moves inwardly, spring means for withdrawing said device from operative position, and a latch arranged to be operated to release the device to the action of said spring means.

15. In a machine of the class described, the combination with a wiper mounted for movement to wipe an upper inwardly over the feather of a sole on a last, of a presser device arranged to be positioned over the sole and to engage the margin of the upper on the opposite side from the wiper for increasing the frictional hold of the wiper on the upper as the wiper moves inwardly, a sole rest, a latch for connecting said presser device to the sole rest to hold the device in operative position, spring means for withdrawing the device from operative position, and means for operating the latch to release the device to the action of said spring means.

16. In a machine of the class described, the combination with end embracing wipers movable to wipe the margin of an upper inwardly over the feather of a sole on a last, and power means for operating said wipers, of a presser device arranged to be positioned on the sole and to project outwardly over the feather of the sole for engagement with the margin of the upper to bend it outwardly over the wipers as the wipers move inwardly, and means automatically operative in time relation to the inward movement of the wipers to withdraw said device from operative position prior to the completion of the operation of the machine on the shoe.

17. In a machine of the class described, the combination with a wiper movable to wipe the margin of an upper inwardly over the feather of a sole on a last, and power means for operating said wiper, of a presser device arranged to project outwardly over the feather of the sole for engagement with the margin of the upper to bend it outwardly over the wiper as the wiper moves inwardly, spring means for withdrawing

said device from operative position, a latch for holding the device in operative position against the tension of said spring means, and means automatically operative to move said latch and release the device.

18. In a machine of the class described, the combination with means for pulling an upper over a last and means for wiping the margin of the upper inwardly over the sole of the shoe, of a presser device arranged to be positioned over the sole and having an outer edge portion adapted when thus positioned to engage the margin of the upper opposite where the pulling of the upper takes place and bend it progressively outward over the wiping means in the over-wiping operation before the upper is released by the pulling means.

19. In a machine of the class described, the combination with a gripper for pulling an upper at the toe of a last and end embracing wipers for wiping the margin of the upper inwardly over the sole of the shoe, of a presser device arranged to be positioned on the sole and to engage the margin of the upper on the opposite side from the wipers for increasing the frictional hold of the wipers on the upper, and means for withdrawing said device from operative position in time relation to the movement of the wipers.

20. In a machine of the class described, the combination with a gripper for pulling an upper over a last and a member for laying the margin of the upper inwardly over the sole of the shoe, of a presser device arranged to be positioned over the sole and to engage the upper on the opposite side from the overlaying member to increase the effective hold of said member on the upper in the overlaying operation, said device being mounted on the gripper for movement into and out of operative position.

21. In a machine of the class described, the combination with a gripper for pulling an upper over a last and a wiper for wiping the margin of the upper inwardly over the feather of the sole of the shoe, of a presser device arranged to project outwardly over the feather of the sole in position to engage the margin of the upper and bend it outwardly over the wiper as the wiper moves inwardly, said device being mounted on the gripper, and means independent of the gripper for maintaining the device in operative position.

22. In a machine of the class described, the combination with a gripper for pulling an upper over a last and a wiper for wiping the margin of the upper inwardly over the feather of the sole of the shoe, of a presser device arranged to project outwardly over the feather of the sole in position to engage the margin of the upper and bend it outwardly over the wiper as

the wiper moves inwardly, said device being mounted on the gripper, a sole rest, and means for connecting said device to the sole rest to maintain the device in operative position during the upper pulling movement of the gripper.

23. In a machine of the class described, the combination with a gripper for pulling an upper over a last and a wiper for wiping the margin of the upper inwardly over the feather of the sole of the shoe, of a presser device arranged to project outwardly over the feather of the sole in position to engage the margin of the upper and bend it outwardly over the wiper as the wiper moves inwardly, said device being mounted on the gripper, a sole rest, a latch for connecting said device to the sole rest to maintain the device in operative position during the upper pulling movement of the gripper, spring means for withdrawing the device from operative position, and means for operating the latch to release the device to the action of said spring means.

24. In a machine of the class described, the combination with a gripper for pulling an upper over a last, of a hold-down mounted on the gripper for engagement with the sole of the shoe, a sole rest, a latch for connecting the hold-down to the sole rest to maintain the hold-down in operative position during the upper pulling operation, and means for operating said latch subsequently to release the hold-down.

25. In a machine of the class described, the combination with a gripper for pulling an upper over a last, of a hold-down mounted on the gripper for engagement with the sole of the shoe, a sole rest, a spring for withdrawing the hold-down from operative position, a latch for locking the hold-down to the sole rest against the tension of said spring, and a device movable with the gripper for operating said latch to release the hold-down.

26. In a machine of the class described, the combination with a gripper for pulling an upper over a last, of a hold-down for engaging the sole of the shoe, said hold-down being mounted on the gripper for movement out of operative position, a spring for withdrawing the hold-down from operative position, a sole rest, a latch carried by the hold-down for locking it to the sole rest, and a lug on the gripper for engaging said latch to release the hold-down from the sole rest.

27. In a machine of the class described, the combination with a toe gripper, of a slide on said gripper, a hold-down for engaging the end portion of the sole of the shoe, said hold-down being pivotally mounted on said slide to permit the gripper to move diagonally forward in the upper pulling operation without moving the hold-

- down, a sole rest, a latch for connecting the hold-down to the sole rest to prevent movement of the hold-down away from the plane of the sole while the gripper pulls 5 the upper, means for operating said latch to release the hold-down from the sole rest, and spring means for returning the hold-down into a normal relation to the gripper when it is thus released.
- 10 28. In a machine of the class described, the combination with means for working an upper over a last, of a sole rest, a hold-down mounted independently of the sole rest, a latch for connecting the hold-down 15 to the sole rest to prevent movement of the hold-down away from the plane of the sole, spring means for withdrawing the hold-down from operative position, and means for operating said latch to release the hold-down to the action of said spring means.
- 20 29. In a machine of the class described, the combination with a gripper comprising jaws relatively movable to grip or to release an upper, and a lever for operating 25 the gripper to pull the upper, of a manually operative device on said lever for effecting a relative opening movement of the gripper jaws, and power operated means movable into engagement with said device 30 to open the jaws in the course of the cycle of operations of the machine.
- 30 30. In a machine of the class described, the combination with an upper pulling gripper comprising jaws relatively movable to 35 grip or to release an upper, and means for laying the margin of the upper over the sole of the shoe, of gripper opening means comprising a member movable to effect a relative opening movement of said jaws proportional to the extent of movement of the member, and a power operated member for imparting movement to said first member to effect a gradual opening of the jaws in the course of the overlaying operation.
- 40 45 31. In a machine of the class described, the combination with a gripper comprising relatively movable jaws and a gripper bar and a casing relatively movable to close or to open said jaws, and means movable to lay the margin of the upper over the sole of the shoe, of a member connected to said casing for moving it to open the jaws progressively to release the upper after the upper has been pulled, and a power operated 50 member mounted for movement with said overlaying means to operate said first member.
- 55 32. In a machine of the class described, the combination with an upper pulling gripper comprising jaws relatively movable to grip or to release an upper, and means movable to lay the margin of the upper inwardly over the sole of the shoe, of means for opening the gripper to release 60 the upper including a member movable to effect a relative opening movement of said jaws proportional to the extent of movement of the member, and a power operated member carried by the overlaying means and movable into engagement with said first member to operate it, one of said members comprising a part adjustable to vary the time of opening of the jaws.
- 65 70 33. In a machine of the class described, the combination with an upper pulling gripper comprising jaws relatively movable to grip or to release an upper, of means for opening the gripper to release the upper including a member movable to effect a relative opening movement of said jaws proportional to the extent of movement of the member, a member mounted for movement into engagement with said first member to operate it, and means for effecting an additional relative movement of said members after their engagement with each other in such a direction as partially to counteract the effect of said operating member and retard the opening of the jaws.
- 75 80 34. In a machine of the class described, the combination with an upper pulling gripper comprising jaws relatively movable to grip or to release an upper, of means for opening the gripper to release the upper including a member movable relatively to the gripper to effect a relative opening movement of said jaws proportional to the extent of movement of the member and movable also bodily with the gripper in the direction of the pull as the jaws relax their hold on the upper, and a member mounted for movement in a direction transverse to the direction of the pull to operate said first member, one of said members having a contact face engaged by the other and inclined to the direction of movement of the operating member to cause the opening of the jaws to be effected gradually by the action of the operating member as the gripper is moved when the gripping pressure is relaxed.
- 85 90 100 105 110 35. In a machine of the class described, the combination with an upper pulling gripper comprising jaws relatively movable to grip or to release an upper, and spring means for moving the gripper to pull the upper and for moving it farther as it releases the upper, of gripper opening means including a member movable relatively to the gripper to effect a relative opening movement of said jaws proportional to the extent of movement of the member and movable also bodily with the gripper as the latter is moved by said spring means, and a member movable in a direction transverse to the direction of the pull of the gripper to operate said first member, one of said members having a contact face engaged by the other and inclined to the direction of movement of the operating member to render 115 120 125 130

gradual the gripper opening effect of said operating member and cause the gripper to slip on the upper while still holding it with substantial pressure as it is retracted by its spring.

36. In a machine of the class described, the combination with a gripper comprising jaws relatively movable to grip or to release an upper, a lever for moving said gripper to pull the upper and a spring through which movement is imparted to said lever to pull the upper and to move the gripper farther as it releases the upper, of gripper opening means including a member mounted on said lever and movable to effect a relative opening movement of said jaws proportional to the extent of movement of the member, and a member mounted for movement in a direction transverse to the direction of the pull of the gripper to operate said first member, one of said members having a contact face engaged by the other and inclined to the direction of movement of the operating member to render gradual the gripper opening effect of said operating member as the gripper is retracted by its spring.

37. In a machine of the class described, the combination with a gripper comprising jaws relatively movable to grip or to release an upper, a lever for moving said gripper to pull the upper and a spring through which movement is imparted to said lever to pull the upper and to move the gripper farther as it releases the upper, of gripper opening means including a member mounted on said lever and movable to effect a relative opening movement of said jaws proportional to the extent of movement of the member, and a member mounted for movement in a direction transverse to the direction of the pull of the gripper to operate said first member, one of said members comprising a part having a contact face engaged by the other and inclined to the direction of the movement of said operating member, said part being adjustable to vary the time of opening of the gripper.

38. In a machine of the class described, the combination with a gripper comprising jaws relatively movable to grip or to release an upper, and a lever for operating said gripper to pull the upper, of gripper opening means comprising a member mounted on said lever and movable to effect a relative opening movement of said jaws proportional to the extent of movement of the member, said member having a contact face inclined to the direction of the pull of the gripper, and a power operated member mounted for movement in a direction oblique to the plane of said face to operate the first member by engagement with said face.

39. In a machine of the class described, the combination with a gripper for pulling

an upper over a last and means movable inwardly to lay the margin of the upper over the bottom of the last, of a device for restraining the gripper from overdrawing movement as the overlaying means moves inwardly, and means constructed and arranged to cause the gripper to relax its hold on the upper and permit the upper to slip as the overlaying means moves inwardly while maintaining sufficient gripping pressure on the upper to prevent substantial loss of the pulling-over tension.

40. In a machine of the class described, the combination with a gripper for pulling an upper over a last and a member movable inwardly to lay the margin of the upper over the bottom of the last, of a device for restraining the gripper from overdrawing movement as the overlaying member moves inwardly, and means constructed and arranged to cause the gripper to relax its holding pressure on the upper sufficiently to permit the upper to slip and then to maintain said pressure substantially constant until the upper has been pulled from the gripper by the action of the overlaying member.

41. In a machine of the class described, the combination with a toe gripper for pulling an upper over a last and end embracing wipers movable to wipe the margin of the upper into lasted position round the toe, of gripper opening means automatically operative in the course of the movement of said wipers to cause the gripper to relax its hold on the upper and permit the upper to slip in the gripper while maintaining sufficient gripping pressure on the upper to prevent substantial loss of the pulling-over tension.

42. In a machine of the class described, the combination with a gripper for pulling an upper over a last, and a wiper movable to wipe the margin of the upper inwardly over the bottom of the last, of gripper opening means comprising a member associated with the gripper and another member movable inwardly with the wiper to operate said first member, said opening means being constructed and arranged to cause the gripper to relax its hold on the upper and permit the upper to slip in the gripper as the wiper moves inwardly while maintaining sufficient gripping pressure on the upper to prevent substantial loss of the pulling-over tension.

43. In a machine of the class described, the combination with an upper pulling gripper comprising jaws relatively movable to grip or to release an upper, and a wiper movable to wipe the margin of the upper inwardly over the sole of the shoe, of gripper opening means including a member movable relatively to the gripper to effect a relative opening movement of said jaws

- proportional to the extent of movement of the member and movable also bodily with the gripper in the direction of the pull as the jaws relax their hold on the upper, and
- 5 a member mounted for movement with the wiper in a direction transverse to the direction of the pull to operate said first member, one of said members having a contact face engaged by the other and inclined to the
- 10 direction of movement of the operating member to render gradual the effect of said operating member and cause the gripper to slip on the upper while still holding it with substantial pressure.
- 15 44. In a machine of the class described, the combination with a toe gripper comprising jaws relatively movable to grip or to release an upper and end embracing wipers movable to wipe the margin of the upper 20 into lasted position round the toe, of gripper opening means comprising a member movable bodily with the gripper in the direction of the pull and movable also relatively to the gripper to effect a relative opening
- 25 movement of the jaws proportional to the extent of movement of the member, and an operating member movable with the wipers in a direction transverse to the direction of the pull to operate said first member, said
- 30 members having their contact faces disposed in such relation to the direction of the pull as to cause the jaws to slip on the upper without entirely releasing it as the wipers move inwardly.
- 35 45. In a machine of the class described, a gripper for pulling an upper over a last, a wiper movable to wipe the margin of the upper inwardly over the sole of the shoe, a presser device for engaging the upper on
- 40 the opposite side from the wiper to increase the frictional hold of the wiper on the upper, and a gripper opening device automatically operative to cause the gripper to relax its hold on the upper and permit the
- 45 upper to slip without entirely releasing it as the wiper moves inwardly.
46. In a machine of the class described, a gripper for pulling an upper over a last, a wiper movable to wipe the margin of the upper inwardly over the sole of the shoe, a presser device arranged to be positioned on the sole and to bend the margin of the upper progressively outward over the wiper as the wiper moves inwardly, gripper opening means comprising a member associated with the gripper and movable to effect a gradual opening of the gripper jaws, and a member movable with the wiper to operate said first member, said members being so
- 50 constructed and arranged as to cause the jaws to relax their hold on the upper and permit it to slip while still maintaining substantial holding pressure upon it as the wiper moves inwardly.
- 55 47. In a machine of the class described,
- a gripper for pulling an upper over a last, a wiper for wiping the margin of the upper inwardly over the sole of the shoe, a presser device for engaging the margin of the upper on the opposite side from the wiper to increase the frictional hold of the wiper on the upper, a tacker movable inwardly with the wiper for fastening the upper, a gripper opening device automatically operative as the wiper moves inwardly to cause the jaws to relax their hold on the upper and permit it to slip while still maintaining a substantial hold on the upper, and means automatically operative to withdraw said presser device from operative position prior to the
- 60 tacking operation.
48. In a machine of the class described, a gripper for pulling an upper over a last, a wiper for wiping the margin of the upper inwardly over the sole of the shoe, a presser device mounted on the gripper for engagement with the margin of the upper on the opposite side from the wiper to increase the frictional hold of the wiper on the upper, a sole rest, a latch connecting said
- 65 presser device to the sole rest, a tacker movable inwardly with the wiper, means automatically operative in the inward movement of the wiper to cause the gripper to relax its hold on the upper and permit it to slip, and a device movable with the gripper as it slips on the upper to operate said latch and release the presser device from the sole
- 70 rest.
49. In a machine of the class described, the combination with a gripper mounted for movement to pull an upper over a last, of a hold-down for engaging the sole of the shoe, and means for producing a wedging action between said hold-down and gripper to force the gripper outwardly from the edge of the shoe bottom in its upper pulling movement.
50. In a machine of the class described, the combination with a gripper mounted for movement to pull an upper over a last, of a sole rest, and a device positioned by said sole rest for wedging the gripper laterally outward from the edge of the shoe bottom in its upper pulling movement.
- 55 51. In a machine of the class described, the combination with a gripper mounted for movement to pull an upper over a last, of a sole rest, and a member arranged to be held by the sole rest from movement inwardly over the sole, said member and the gripper having co-operating portions constructed to wedge the gripper laterally outward from the edge of the shoe bottom in its upper pulling movement.
- 56 52. In a machine of the class described, the combination with a gripper mounted for movement to pull an upper over the toe end of a last, of a sole rest, and a hold-down arranged to engage the sole in front of the

sole rest and to be held by the sole rest from rearward movement over the sole, said hold-down and the gripper having co-operating portions constructed to wedge the gripper forwardly in its upper pulling movement.

53. In a machine of the class described, the combination with a wiper movable to wipe the margin of an upper inwardly over the bottom of a last, of a member arranged to be positioned on the sole of the shoe to engage the margin of the upper and by the inward movement of the wiper to bend said margin progressively outward over the wiper in the overwiping operation, and mechanism automatically operative to withdraw said member from operative position while the wiper is applying holding pressure to the margin of the upper.

54. In a machine of the class described, the combination with a sole rest, and a wiper for wiping the margin of an upper inwardly over the sole, of a member arranged relatively to said sole rest for engagement with the marginal portion of the sole of a shoe positioned by said sole rest and constructed to provide a restricted opening between it and the feather of the sole to receive the upper forced inwardly by the wiper, and mechanism automatically operative to withdraw said member from operative position after the wiper has forced the margin of the upper into said opening.

55. In a machine of the class described, the combination with a wiper support and a wiper for wiping the margin of an upper inwardly over the bottom of a last, of a member arranged to engage the margin of the upper and to press said margin against the wiper as the wiper moves inwardly, and mechanism arranged to be rendered operative by the inward movement of the wiper support to withdraw said member from operative position.

56. In a machine of the class described, the combination with means for pulling an upper over a last and for holding the upper under tension, of means for wiping the margin of the upper inwardly over the bottom of the last while the upper is retained under control of said pulling means, a member arranged to engage the margin of the upper and press it against said wiping means in the overwiping operation, and mechanism automatically operative to withdraw said member from operative position after the wiping means has arrived in position to hold the upper.

57. In a machine of the class described, the combination with a gripper for pulling an upper over a last, and a wiper for wiping the margin of the upper inwardly over the bottom of the last, of mechanism automatically operative in the overwiping operation to relax the pressure of the gripper on

the upper and permit the upper to slip while still maintaining control of the upper by the gripper, and an abutment member arranged to co-operate with the wiper to engage the upper with increasing pressure as the upper slips in the gripper.

58. In a machine of the class described, the combination with a gripper for pulling an upper over a last, and a wiper for wiping inwardly over the bottom of the last a portion of the upper pulled by said gripper, of a member arranged to engage the margin of the upper and press it against the wiper in the inward movement of the wiper, and mechanism automatically operative to withdraw said member from operative position after the wiper has arrived in position to hold the upper against substantial loss of the pulling over tension.

59. In a machine of the class described, the combination with a gripper for pulling an upper over a last, and a wiper for wiping the margin of the upper inwardly over the bottom of the last, of a member for engaging the margin of the upper and pressing it against the wiper as the wiper moves inwardly, and means automatically operative to relax the pressure of the gripper on the margin of the upper in the overwiping operation while still maintaining control of said margin by the gripper and to withdraw said member from operative position after the wiper has arrived in position to hold the upper against substantial loss of the pulling-over tension.

60. In a machine of the class described, the combination with a gripper for pulling an upper over a last, and a wiper for wiping the margin of the upper inwardly over the bottom of the last, of a member for engaging the margin of the upper and pressing it against the wiper as the wiper moves inwardly, mechanism automatically operative in the inward movement of the wiper to relax the pressure of the gripper on the margin of the upper and permit the gripper to slip on said margin while it still maintains control of the upper, and mechanism controlled by said gripper as it slips on the upper for withdrawing said member from operative position.

61. In a machine of the class described, the combination with a gripper and means for operating it to pull an upper over a last, and means for laying the margin of the upper inwardly over the bottom of the last, of mechanism automatically operative in the overlaying operation to relax the pressure of the gripper on the upper and permit the upper to slip in the gripper while maintaining sufficient gripping pressure upon it to prevent substantial loss of the pulling-over tension.

62. In a machine of the class described, the combination with a gripper for pulling

an upper over a last, and means movable to lay the margin of the upper over the bottom of the last, of mechanism arranged to be operated by the movement of said overlaying means to relax the pressure of the gripper on the upper and permit the upper to slip while retaining control of the upper by the gripping pressure as the overlaying means moves inwardly.

63. In a machine of the class described, the combination with means for working an upper over a last, of a sole rest, a holddown supported independently of the sole rest for engagement with the marginal portion of the sole, a connection between said holddown and the sole rest for maintaining the holddown in position to engage the sole, and means for withdrawing the holddown from operative position.

64. In a machine of the class described, the combination with means for laying the margin of an upper over the bottom of a last, of a sole rest, a holddown mounted independently of the sole rest for engagement with the marginal portion of the sole, a connection between said holddown and the sole rest for maintaining the holddown in operative position, and mechanism arranged to be controlled by the movement of said overlaying means for disconnecting the holddown from the sole rest.

65. In a machine of the class described, the combination with a gripper for pulling an upper over a last, of a holddown mounted on said gripper for engagement with the marginal portion of the sole of the shoe, means movable to lay the margin of the upper inwardly over the sole, and mechanism automatically operative in the inward movement of said overlaying means to cause the holddown to withdraw from the sole.

66. In a machine of the class described, the combination with a gripper for pulling an upper over a last, of a holddown mounted on the gripper for engagement with the marginal portion of the sole of the shoe, a sole rest, a connection between said holddown and the sole rest for maintaining the holddown in operative position, means movable to lay the margin of the upper inwardly over the sole, and mechanism controlled by the inward movement of said overlaying means for disconnecting the holddown from the sole rest.

67. In a machine of the class described, the combination with a gripper for pulling an upper over a last, of a holddown mounted on said gripper for engagement with the marginal portion of the sole of the shoe, means for retaining the holddown in operative position independently of the gripper, means for imparting a withdrawing movement to the gripper after the upper pulling operation, and mechanism controlled by said withdrawing movement of the gripper for releasing the holddown from said retaining means.

68. In a machine of the class described, the combination with a gripper for pulling an upper over a last, of a holddown member for engaging the sole of the shoe, means for relaxing the pressure of the gripper on the upper and for imparting to the gripper a withdrawing movement after the upper has been pulled, and mechanism controlled by said withdrawing movement of the gripper for withdrawing said holddown member from operative position.

In testimony whereof I have signed my name to this specification.

WILLIAM C. STEWART.
